UNITED STATES PATENT OFFICE.

PETER J. GORDON, OF SAG HARBOR, NEW YORK, ASSIGNOR TO JOSEPH FAHYS & CO., OF NEW YORK, N. Y., A CORPORATION OF NEW YORK.

DESIGN FOR A SPOON OR SIMILAR ARTICLE.

Application filed October 23, 1925. Serial No. 15,237. Term of patent 7 years.

To all whom it may concern:

Be it known that I, PETER J. GORDON, a citizen of the United States of America, and a resident of Sag Harbor, county of Suffolk, State of New York, have invented a new, original, and ornamental Design for Spoons or Similar Articles, of which the following is a specification, reference being had to the accompanying drawing, forming part thereof.

Figures 2 and 3 are cross-sections taken on Figure 1 at points directly opposite.

I claim:

The ornamental design for a spoon or similar article, as shown.

PETER J. GORDON.
